Application July 14, 1945, Serial No. 605,071

24 Claims. (Cl. 244—148)

1

This invention relates to improvements in parachute packs.

The primary object of this invention is the provision of a parachute pack of the back pack type constructed to conform to the shape and contour of the back of a wearer and of a nature to readily flex longitudinally to permit the wearer to stoop and move about with ease, and under such circumstances that the pack will still conform to the wearer's back without presenting projecting portions.

A further object of this invention is the provision of a form fitting back type parachute pack constituting an improvement upon the Erwin House Nichols form fitting parachute pack set forth in United States Patent 1,882,086, in that the container presents maximum longitudinal and lateral space for receiving the parachute and shroud lines under such condition that the pack will present a rather thin and flexible construction which will conform to the body of a wearer and yet admit of bending so that the wearer may move longitudinally and twist transversely in a comfortable manner.

A further object of this invention is the provision of an improved parachute pack which embodies a container having a minimum of metal shape providing parts, and so constructed that the parachute canopy and shroud lines may with facility and safety be packed in the container under such circumstances as to prevent injury thereto and yet provide a pack which is relatively thin and entirely flexible to admit of normal movement of an aviator, whether he be a pilot, parachutist, gunner, etc.

With present aircraft it is sometimes necessary for aviators to move about in confined spaces. With that in mind, it is a purpose of the present invention to provide a form fitting parachute back pack without cumbersome projection and protuberances, and which will flexibly conform to the shape of the wearer's body.

A further object of this invention is the provision of an improved form fitting flexible parachute pack associated with a single point release harness in an improved relation.

A further object of this invention is the provision of an improved reinforced parachute pack container.

A further object of this invention is the provision of improved position holding flaps for parachute back packs associated in an improved relation with parachute body attaching harness.

Other objects and advantages of this invention

2

will be apparent during the course of the following detailed description.

In the accompanying drawings wherein for the purpose of illustration are shown different forms of the improved parachute back pack—

Figure 1 is a perspective view of one form of the improved pack and single point release harness associated in an improved relation therewith.

10 Figure 2 is a normal front view of the parachute pack in a packed condition.

Figure 3 is a normal rear view of the parachute pack in a packed condition.

15 Figure 4 is a longitudinal cross sectional view taken thru the improved pack substantially on the line 4—4 of Figure 3.

Figure 5 is a transverse cross sectional view taken substantially on the line 5—5 of Figure 3.

20 Figure 6 is a view showing the flaps of the pack open and the parachute canopy removed, with the shroud lines tucked in place and the riser webs extending from the pack.

Figures 7 and 8 are cross sectional views taken substantially on their respective lines in Figure 6 25 of the drawings, and showing more particularly reinforcing improvements in the pack.

Figure 9 is a developed view showing the association of the various metal frame details of the pack container.

30 Figure 10 is a perspective view of another form of the improved form fitting parachute back pack.

Figure 11 is a normal front view of the pack of Figure 10.

35 Figure 12 is a normal rear view of the pack of Figure 10.

Figure 13 is a longitudinal cross sectional view taken thru the second form of improved parachute pack substantially on the line 13—13 of Figure 12.

40 Figure 14 is a transverse cross sectional view taken thru the pack of Figure 12 substantially on the line 14—14 of Figure 12.

Figure 15 is a view of the pack showing the flaps open and the relation of packed shroud lines therein.

45 Figures 16, 18 and 19 are cross sectional views taken substantially on their respective lines shown in Figure 15 of the drawings, showing structural features of the frame and container.

Figure 17 is a perspective developed view showing the metal frame structure of the container.

Referring to the form of parachute equipment A shown in Figures 1 to 9 inclusive, the same includes a pack B and single point release har-

ness C' associated in an improved relation therewith. The harness is of the single point release type including a U-shaped sling structure 25 having riser webs 26 and 27 which extend into the pack container as shown in Figure 6 of the drawings. This harness includes a single point release coupling 30, the general purpose of which is set forth in U. S. Patent 1,899,656. The single point release harness includes back straps 31 and 32 which cross at the back of the wearer and are secured by adapters 33 to the riser webs of the harness and extend downwardly at the front of the wearer at 34 and 35 and are threaded thru fastener parts 36 adapted for detachable connection with the single point release coupling 30. From the fastener parts 36 the straps 34 and 35 are adjustably connected together to form a back cross strap 38. The back straps 31 and 32 at their lower ends are stitched at 39 to the riser webs of the U-shaped sling. The harness furthermore includes leg straps 40 and 41 secured upon the seat portion 42 of the sling 25 and extended therefrom around the riser webs of the sling, as shown in Figure 1, to provide leg receiving loops. The ends of these straps 40 and 41 are adjustably provided with loops and adapters to support fastener parts 45 for detachable connection with the single point release coupling 30.

Referring to the pack B, the same generally includes a container C adapted to receive a parachute canopy D and shroud lines E in packed relation therein.

The container C is of an improved construction, best adapted to receive the canopy and shroud lines therein to provide a pack which is relatively thin and extended both longitudinally and transversely to the maximum dimensions, and under such conditions that the pack may readily flex to conform to the bending of the wearer's body without any projecting extensions which might catch upon some part of the aircraft.

Referring to the detailed construction of the container C, the same includes what is conventionally referred to, in the parachute art, as a back or body portion 50, of flexible fabric material, having top and bottom flaps 51 and 52 respectively associated therewith and side flaps 53 and 54. The general configuration of the container back portion 50 is rectangular, the sides being straight, but the upper and lower margins being convexly curved as best shown in Figure 3 of the drawings. This back portion 50 is generally formed of a double ply fabric between which are positioned the frame portions of the unitary frame structure shown in Figure 9.

The frame structure includes the upper and lower frame pieces 60 and 61 and the intermediate frame pieces 62. The intermediate frame pieces 62 each consists of parallel longitudinally curved bar portions 67 which may be made of spring metal, plastic or any approved material which presents the desired springiness and semi-rigidity to hold the shape of the pack. That is also true of the entire frame structure. The bar portions 67 are secured together at their ends in parallelism by the end bar pieces 68.

The end pieces 60 and 61 are similar in construction; each including a transversely flexible structure 62^a similar in nature to the parts 62, each including parallel bars 63 which are longitudinally curved and secured at their ends by bar portions 64. The frame structure 60 and 61 furthermore include the contiguous side pieces 65 (in line with the bar portions 64) and at the ends the pieces 60 and 61 have flexible cross portions

66 which are endwise convex and likewise convexly curved thruout their lengths.

The frame structure shown in Figure 9 defines the shape of the pack; the curved portions 66 of the frame fixing the curved shape of the pack at its upper and lower margins as shown in Figure 3. These frame portions are placed between the plies of material of the back of the container and intimately fit in position by stitching which borders all of the bar portions of these various frame pieces.

It will be noted that the frame structure when secured in position presents a back pack container with considerable space between adjacent bar portions 62 and 62^a so that the pack has easy longitudinal flexing. Of course the spring nature of the frame work will permit transverse flexing and actually the bar portions are transversely flexed when the container is closed to admit of ready opening of the flaps of the container. This tensioning of the bar portions when the container is closed, with the parachute canopy therein, does not interfere with proper curvature of the framework in conformity to the back of the wearer, since the harness will hold the back pack intimately against the shape of the wearer's back.

It will be noted that the side flaps 53 and 54 extend substantially the full length of the container with the exception of the bowed ends 66 of the frame work. In width they are sufficient to overlap in conventional manner. The top and bottom flaps 51 and 52 are relatively short.

The outer side flap 54 is provided with grommets 70 and the other side flap 53, as well as the top and bottom flaps 51 and 52, are provided with cones adapted to interfit in conventional manner with the grommets 70. As shown in Figure 3 of the drawings, a rip cord housing 72 is secured at 74 centrally upon the outer surface of the top flap 51 and this housing extends along the riser web of the harness and is secured at 75. The rip cord extends thru this housing and has a rip cord handle 76 which is pocketed in conventional relation on the riser web of the harness, as shown in Figure 1.

An important feature of the invention is the provision of flexible fabric webbing reinforcement along the sides of the container exteriorly thereon, generally designated at 80; such webbing including a portion 81 secured as by stitching to the exterior of the fabric back 50 and extending around the margin of the back and at 82 over the external surface of each of the side flaps 53 and 54, as best shown in Figure 8. This webbing is rather stiff and reinforces the sides of the pack against wear; holds the shape of the pack, and prevents the pinching of the shroud lines and canopy within the pack.

An improved association of shroud line retaining pockets in relation to the frame structure is associated with the container consisting of strips 84 and 85 secured upon the inside surface of the back of the pack, defining pockets 86 for receiving the ends of the shroud lines when tucked in zig-zag fashion crosswise upon the back of the pack, as shown in Figure 6; the pockets 86 being all located either within the large open part of end frame pieces, or in the spaces between the frame portions 62 and 62^a. These pockets do not directly overlie any part of the framework, and of course, as an incident of flexing of the framework, the pocket and the shroud tucked therein will not be appreciably disturbed. This prevents chafing of the shroud lines, etc.

As a cooperative part of the pack container

structure, to assist in the holding of the same snugly at the sides of the wearer, we prefer to provide positioning flaps 90 and 91, stitched at 92 externally upon the web portion 82 of the container. These flaps 90 and 91 extend for the major length of the side margins of the pack container. They are of triangular formation and constructed of double ply material with transverse stitching making a flexible but more rigid structure than the container flaps. At the outer corners these positioning flaps 90 and 91 are provided with harness receiving loops 93.

Referring to the association of the one piece point release harness C' upon the pack structure B, we provide a transverse harness securing strip 94 upon the normal outer surface of the back of the container, as shown in Figure 1, stitched to the two plies of the back 50 of the container and at its ends having snap fasteners 95 for detachably holding the upper cross pieces 31 and 32 of the harness in position upon the pack. Guard strips 96 having snap fasteners 97 are provided upon the back 50 of the pack at the sides thereof for holding the lower ends of the cross pieces 31 and 32 of the harness in place. As shown in Figure 2 of the drawings, these strips are continued and provided with snap fasteners 98 at their lower ends for detachably holding the cross piece of the harness in position.

The position holding flaps 90 and 91 receive the riser webs of the sling of the harness therein just above the seat portion 42 at a point just below where the leg straps 40 and 41 are turned about the riser webs. Thus, these loops 93 hold the leg straps in position and define a means of properly locating the leg straps, from which position they cannot ride down the riser webs.

It will be apparent from the foregoing that with the single point release harness, in its association, above defined, with the pack, will insure that the pack will be held snugly along the sides and conform to the contour of the wearer's back. The position flaps 90 and 91 hold the pack snugly at the sides and also are a means of holding the harness properly upon the body.

Referring to the form of pack and harness structure shown in Figures 10 to 19 inclusive, therein is shown the harness C' which conforms in all essential characteristics to the harness C' above described, and the same reference characters have been applied to both harnesses. However, in association with the harness C' of the form of invention shown in Figure 10, is an improved pack G which, while possessing some of the characteristics of the form of pack C above described, is different in some respects, altho the purpose of the invention and the functions served by it are in the main the same as that above defined for the pack B.

Referring to the pack G, the same includes a container H wherein it is adapted to releasably store a canopy K and shroud lines L in a manner to be subsequently mentioned.

The pack G is characterized by the fact that it is extremely flexible and uses an exact minimum of flexible metal or plastic spring material for reinforcing and holding the position of the pack.

The container H includes what is referred to as the normal back portion 100, which is of double ply material. The side flaps 101 and 102 are provided, extending along the entire length of the pack with the exception of the upper bowed portion of the pack enclosed. A bottom free flap 104 is provided along the bottom margin of the back wall 100, and a pocketed flap 105 is secured

upon the back wall structure 100 of the pack. This flap is not entirely free, in that its upper margin 106 is convexly curved upwards and stitched to the back wall of the flap, presenting a pocket which receives part of the canopy structure. It is an aim of this invention to provide as long and wide a container surface as possible so that the pack will be relatively thin at all points and yet conform to the curvature of the back of the wearer.

Preferably three spring metal frame pieces 110 are provided between the plies of the back wall 100; one of them being placed midway between the top and bottom of the pack and the other about one-sixth of the distance from the top and bottom margins of the pack container. These pieces 110 may be of spring metal or plastic or other material and extend from side margin to side margin of the pack. They are of double bar construction, each including bar portions 111 and 112 secured at their ends by end bar portions 113^a. The bars 111 and 112 between their ends may have an elongated connecting portion 114 which adds to the longitudinal resiliency of these members 110, since it is at this point that the spring frame portion fulcrums during transverse flexing thereof. The terminals of the bar portions 110 are shown in Figure 14 short of the extreme side marginal edges of the container.

The lower portion 120 of the back wall structure 100 of the container, below the lowermost frame piece 110, as shown in Figure 15 of the drawings, is completely flexible, yet reinforced by means of an additional piece of webbing or fabric placed between the plies of the back 50, as indicated at 120^a in Figure 19 of the drawings. The plies and this webbing are held together by means of transverse stitching 121 in closely spaced relation. This structure is sufficient to hold the position of the pack when the parachute canopy and shroud lines are packed therein. The upper part of the back wall structure 100 is similarly formed, above the uppermost frame piece 110. This portion of the back wall structure is indicated at 125 in Figures 15 and 18 of the drawings, and includes a fabric piece 125^a (see Figure 18) between the plies of the back wall, stiffened by means of closely spaced transverse stitching indicated in dotted lines in Figure 15 of the drawings at 126. This flap structure 125, forming a part of the back wall, extends above the top margin of the flap 105. It is adapted to overlie the back below the neck of the wearer in a comfortable position, holding of the back structure upon the wearer.

The normal transverse curvature of the spring bars or members 110 are flexed somewhat when the pack is closed, but they are still curved, as shown in Figure 14, to comfortably conform to the back of the wearer.

The structure of the container along the side margins of the pack is important in that the flaps 101 and 102 are provided with reinforced flexible webbing 130 stitched upon the respective flaps at 131, as shown in Figure 16 of the drawings; this webbing and the flaps 101 and 102 being stitched at 132 upon the extension portion 133 of the back structure 110 beyond the ends of the frame pieces 110, as shown in Figure 16. This webbing 130 adds reinforcement and stiffness to the sides of the pack for the purpose of reinforcement, shape holding and prevents pinching of the material within the container.

The pack also includes body positioning flaps 135 and 136 secured along the side margins of

the container, extending from the bottom upwardly to adjacent the top of the pack. These flaps 135 and 136 are of multiply webbing reinforced material stitched to add stiffness thereto. Each of them are provided with harness receiving loops 137 secured in closed relation by snap fasteners 138 shown in Figure 11 of the drawings. These flaps are additionally provided with harness retaining strips 139 secured by snap fasteners 140, for a purpose to be subsequently mentioned.

It will be noted that the wall portion 125 at the top of the back of the container is provided with harness attaching extensions 140^a which extend over the shoulders of the wearer to protect the wearer's shoulders from harness adapters, etc., and to insure body conforming of the outline of the container to the wearer.

With reference to the association of the harness C' with the pack G, the back straps 31 and 32 are secured upon the portion 125 of the back wall of the pack by a snap fastener retained strip 141 where these straps cross. Additionally, a retaining strip 142 is provided at its ends with snap fastener held portions 143 which secure the upper ends of these back crossing straps in position upon the extreme top of the wall portion 125, and at the upper tips of the extensions 140^a are provided snap fastener held strips 145 which hold the shoulder portions of the harness thereupon. The straps 31 and 32 where they extend to the flaps 135 and 136 are held in place by the snap fastener held strips 139 above described, as shown in the drawings, and the waist portion formed by adjustable connection of the lower parts of the straps 31 and 32 are held by other snap fastener held strips 147, shown best in Figure 11 of the drawings.

The leg straps 40 and 41 are threaded about the riser webs of the sling and the snap fastener loops 137 of the side flaps 135 and 136 engage the riser webs of the harness; the leg straps 40 and 41 being located between the respective loops of these flaps in the relation shown in Fig. 10. This holds the position of the leg straps and insures accuracy in the positioning of the flaps against riding up or down along the riser webs. In this manner the side flaps 135 and 136 are assured of snug fitting about the sides of the body; preventing any exposed side margins of the pack, liable to catch upon objects during movement of the wearer.

From the foregoing description of the pack G it will be appreciated that the same will be extremely flexible longitudinally, and with respect to the upper and lower portions this will be particularly true, because of the stiff yet yieldable reinforced portions of the back wall structure.

The ends of the harness webs extend into the container of the pack over the portions 140^a and the shroud lines are preferably longitudinally secured upon the wall 100 of the pack in pockets 150 formed by strips which are placed immediately below the upper frame piece 110 and immediately above the lower frame piece 110. If desired, these pockets may be placed to position the strands of shroud lines crosswise. The canopy K is packed in the container with a portion extending into the pocket formed by the upper flap 105.

It will be noted that the housing 151 for the rip cord is connected at its lower end upon the harness riser web and at its upper end it is connected on the free end of the flap 105, at 152 (see Figure 11). The flap 102 is provided with

grommets 155 adapted to receive the cone structures of flaps 101, 104 and 105.

In addition to other features common to both forms of invention, it will be noted that the rip cord extends thru the cones of the flaps in the usual manner, as shown in Figures 3 and 12 of the drawings. Also, in both forms of invention elastics 113 are provided which are positioned over the frame pieces and extend over the sides of the pack for attachment to the side flaps. Tubular sheath portions may be provided upon the wall structure of the container to hold these elastics in place. Due to the spaced bar constructions of the cross springs, the elastics and their sheaths can socket between the bars without resulting in body discomfort to the wearer. Also, pilot parachutes 170 may be provided, as shown in the longitudinal sectional views of Figures 4, 5, 13 and 14, separated from the main canopy by auxiliary flaps 171 placed upon the side flaps of the container. Also, safety flaps may be provided for housing the rip cord and grommet and cone structures as is usual.

Various changes in the shape, size and arrangement of parts may be made to the forms of invention herein shown and described, without departing from the spirit of the invention or the scope of the following claims.

We claim:

1. In a parachute pack, the combination of a flexible fabric container, and transverse flexible form retaining strips secured to the back of the container and terminating short of the extreme side edges of the container, said strips being of non-fabric material and each consisting of relatively spaced but relatively connected multiple bar portions.

2. In a form fitting back pack for parachute equipment the combination of a container including a foundation wall, side flaps secured to said wall, top and bottom flaps secured to said wall, resilient frame members positioned transversely upon the foundation wall in spaced relation, and side wall forming fabric reinforcement secured directly at the juncture of said sides of the foundation wall and side flaps and extending along said juncture and partially across each of said side flaps, a parachute canopy, shroud lines, and means for securing said shroud lines and canopy within the pack container.

3. In a form fitting back pack the combination of a container including a foundation wall having enclosure flaps, means for detachably connecting said flaps together to form a container for receiving a parachute and shroud lines, frame means in said foundation wall, side walls of stiff fabric reinforcement along the sides of said foundation wall, and harness attaching side flaps connected with said stiff fabric reinforcement.

4. In a form fitting back pack for parachute equipment the combination of a container including a foundation wall and releasably connected flaps for receiving a parachute in enclosed relation therein, and a plurality of frame pieces relatively narrow and extending in length crosswise upon the foundation wall, said frame pieces being flexible yet sufficiently springy to hold the shape of the pack and flex under body movement of the wearer, said frame pieces being of closely spaced double bars secured together at their ends.

5. In a form fitting back pack for parachute equipment the combination of a container including a foundation wall and releasably connected flaps for receiving a parachute in enclosed relation therein, and a plurality of frame pieces relatively narrow and extending in length crosswise upon the foundation wall, said frame pieces being flexible yet sufficiently springy to hold the shape of the pack and flex under body movement of the wearer, said frame pieces being of closely spaced double bars secured together at their ends.

tion therein, a plurality of frame pieces relatively narrow and extending in length crosswise upon the foundation wall, said frame pieces being flexible yet sufficiently springy to hold the shape of the pack and flex under body movement of the wearer, said frame pieces being of closely spaced double bars secured together at their ends, and flap opening elastic means secured upon the foundation wall and extending along frame pieces between the bars thereof.

6. In a back pack construction for parachutes the combination of a foundation wall, flaps connected with the foundation wall marginally thereof, means to releasably connect said flaps together to enclose a parachute and shroud lines, upper and lower spring material frame pieces having convexly arcuate upper and lower portions adapted to curve the pack at the top and bottom thereof, and independent cross frame pieces of spring material connected with the foundation wall between the upper and lower frame pieces above mentioned and independent thereof, said upper and lower frame pieces and the intermediate frame pieces each including spaced double bar portions in close relation.

7. In a back pack construction for parachutes the combination of a foundation wall, flaps connected with the foundation wall marginally thereof, means to releasably connect said flaps together to enclose a parachute and shroud lines, upper and lower spring material frame pieces having convexly arcuate upper and lower portions adapted to curve the pack at the top and bottom thereof, and independent cross frame pieces of spring material connected with the foundation wall between the upper and lower frame pieces above mentioned and independent thereof, said upper and lower frame pieces and the intermediate frame pieces each including spaced bar portions in close relation, said frame pieces all terminating short of the side marginal extremities of the foundation wall, and elastic flap opening means secured upon the foundation wall extending along said frame pieces between the individual bars thereof and around the sides of the container and being attached to the respective side flaps of said container.

8. In a form fitting thin parachute pack the combination of a foundation wall of substantially rectangular formation having relatively wide side flaps secured thereto, short top and bottom flaps, relatively independent spring frame pieces secured independently upon the foundation wall, and fabric shape holding and reinforcing webbing secured upon said pack at the side margins of said foundation wall and extending upwardly along said side flaps and partially thereacross.

9. In a form fitting thin parachute pack the combination of a foundation wall of substantially rectangular formation having relatively wide side flaps secured thereto, short top and bottom flaps, relatively independent spring frame pieces secured independently upon the foundation wall, fabric shape holding and reinforcing webbing secured upon said pack at the side margins of said foundation wall and extending upwardly along said side flaps and partially thereacross, and position holding flaps secured externally upon said side flaps at the locational securement of said reinforcing webbing.

10. In a form fitting back pack for parachutes the combination of a container including a foundation wall having flexible enclosure flaps connected marginally thereabout, said foundation wall having a plurality of relatively spaced spring

frames which are transversely flexible and normally curved terminating short of the extreme side margins of said foundation wall.

11. In a form fitting back pack for parachutes the combination of a container including a foundation wall with enclosure flaps for the parachute, said foundation wall having a plurality of relatively spaced spring frames which are transversely flexible and normally curved, terminating short of the side margins of said foundation wall, and side wall providing reinforced shaping fabric secured at the juncture of said foundation wall and side flaps and extending upwardly along the latter.

15. 12. In a form fitting parachute pack the combination of a foundation wall having multiple ply fabric reinforced upper and lower portions covering a substantial area of said foundation wall, transversely positioned resilient frame pieces upon the foundation wall between the fabric reinforced upper and lower portions, and flexible enclosure flaps for enclosing the parachute and shroud lines marginally connected upon the foundation wall.

20 13. In a form fitting parachute pack the combination of a foundation wall including fabric reinforced upper and lower portions, transversely positioned resilient frame pieces upon the foundation wall between the fabric reinforced upper and lower portions, enclosure flaps for enclosing the parachute shroud lines upon the foundation wall, said frame pieces terminating short of the extremities of the side margins of the foundation wall, and fabric stiffener reinforcement upon the side flaps adjacent the side margins of said foundation wall.

25 14. In a form fitting parachute pack the combination of a foundation wall including fabric reinforced upper and lower portions, transversely positioned resilient frame pieces upon the foundation wall between the fabric reinforced upper and lower portions, enclosure flaps for enclosing the parachute and shroud lines upon the foundation wall, said frame pieces terminating short of the extremities of the side margins of the foundation wall, fabric stiffener reinforcement upon the side flaps adjacent the side margins of said foundation wall, and pocket means secured upon the foundation wall for releasably receiving shroud lines in longitudinal extension upon said foundation wall.

30 15. In a form fitting parachute pack the combination of a foundation wall, transverse spring frame pieces mounted as a part of said foundation wall, said frame pieces being transversely yieldable, said foundation wall above the uppermost frame piece having flexible fabric reinforcement and the foundation wall below the lowermost frame piece being fabric reinforced, flaps associated with the upper and lower fabric reinforced portions of said foundation wall, and side flaps for the foundation wall, said top flap being disposed intermediate the upper and lower portions of said upper fabric reinforced portion of the foundation wall and shaped to provide a downwardly facing pocket, and means for releasably holding said flaps in parachute canopy enclosing relation.

35 16. In a form fitting back pack for parachutes the combination of a foundation wall, transversely yieldable metal spring frame pieces in independent relation upon foundation wall, side flaps, side reinforcement of webbing material secured to said side flaps adjacent the connection of the same with the sides of said foundation wall, up-

11

per and lower fabric reinforced portions as a continuation of the foundation wall above and below the frame pieces above mentioned, said foundation wall at the top thereof above the upper fabric reinforcing portion providing spaced harness attaching extensions.

17. In a form fitting parachute back pack the combination of a container formed of a flexible fabric foundation wall, flexible fabric side walls connected therewith, and flexible fabric top and bottom flaps connected with the foundation wall, a plurality of transversely flexible pack shaping springs connected in spaced independent relation across the foundation wall short of the upper and lower portions thereof, fabric reinforcement upon the upper and lower portions of said foundation wall above and below the extreme spring members positioned therein to laterally and longitudinally stiffen said foundation wall, side wall fabric reinforcements secured to the side flaps adjacent to the extreme margins of the foundation wall, and means to releasably enclose said side, top and bottom flaps upon a parachute canopy.

18. In a parachute pack construction the combination of a flexible fabric foundation wall of substantially rectangular appearance, transverse flexible form retaining strips secured to the foundation wall normal to the major axis of the container, each of which terminates at its ends a short distance from the extreme side edges of the foundation wall, side enclosure flaps of a flexible nature marginally secured to the side edges of the foundation wall beyond the ends of said retaining strips, and flexible end closure walls connected to the ends of the foundation wall.

19. In a parachute pack construction the combination of a foundation wall of flexible construction, flaps connected marginally with the foundation wall, means to releasably connect said flaps together to enclose a parachute and its shroud lines, a plurality of elongated transversely flexible springy form retaining members connected to the foundation wall each formed of relatively spaced bar portions, and flap opening elastics connected with the flaps and with the foundation wall extending parallel within the space between the spaced bars of said frame pieces.

20. In a form fitting parachute back pack the combination of an elongated foundation wall of flexible material, top and bottom flaps connected with said foundation wall, side flaps connected with said foundation wall, means to releasably connect said flaps together to enclose a parachute canopy and shroud lines within the pack, transversely extending springy frame pieces connected to the foundation wall in relatively spaced relation, and shroud line retaining pockets secured upon the foundation wall adjacent to the side flaps with the openings thereof facing in a line normal to the major axis of the foundation wall.

21. In a form fitting back pack for parachutes the combination of a container including a foundation wall with enclosure flaps for the parachute, said foundation wall having a plurality of relatively spaced spring frames of a transversely flexible nature secured thereto, the ends of said springs terminating short of the side margins of the foundation wall, and side wall providing reinforcing fabric secured at the juncture of the foundation wall and side flaps and extending marginally along the foundation wall and partially across each of the side flaps.

22. In a container construction for parachute

75

12

packs the combination of a foundation wall of flexible material having marginally connected therewith a plurality of enclosure flaps, frame springs of flexible springy material connected to remote ends of the foundation wall in shape retaining relation therefor each including a pair of relatively spaced bar portions, and a plurality of independent frame springs connected to the foundation wall between the aforementioned end frame springs and each of which intermediate frame springs consists of a pair of relatively spaced bar portions.

23. In a form fitting back pack for parachutes the combination of an elongated foundation wall of flexible material, side flaps marginally connected to the foundation wall, a bottom end flap marginally connected to the bottom end of the foundation wall, and a form shaped curved flexible flap secured upon the pack forming surface of the foundation wall at the top end thereof short of the extreme edge thereof, the bottom portion of the foundation wall for an appreciable area being reinforced with stiff flexible material upwardly of the flap connected at the bottom of the foundation wall, and the top portion of the foundation wall both outwardly beyond and downwardly of the top curved flap being reinforced with stiffening material thereacross.

24. In a form fitting back pack for parachutes the combination of an elongated foundation wall of flexible material, side flaps marginally connected to the foundation wall, a bottom end flap marginally connected to the bottom end of the foundation wall, and a form shaped curved flexible flap secured upon the pack forming surface of the foundation wall at the top end thereof short of the extreme edge thereof, the bottom portion of the foundation wall for an appreciable area being reinforced with stiff flexible material upwardly of the flap connected at the margin of the foundation wall, and the top portion of the foundation wall both outwardly beyond and downwardly of the top curved flap being reinforced with stiffening material thereacross, and transversely extending frame springs connected to the foundation wall between the reinforced lower and upper portions of the foundation wall.

HAROLD G. ROGERS.
CHESTER C. KAJDAN.
